UNITED STATES PATENT OFFICE

GEORGE L. LANE, OF ARDMORE, PENNSYLVANIA

TENNIS-NET-STRETCHING DEVICE

Application filed September 14, 1928. Serial No. 306,082.

This invention relates to devices useful in connection with tennis equipment to support and maintain the nets under lengthwise tension for assurance against sagging. Generally speaking, my present device is similar in construction and operation to that shown and described in U. S. Patent No. 1,632,553 granted me under date of June 14, 1927, wherein a slide, vertically adjustable on the net post for the purposes of initially taking up the slack of the net, carries toggle means whereby the suspension rope for the net may be subsequently placed under the required tension.

The patented structure supra is however designed for use with metallic posts that are removable from sockets sunken into the ground, and it is to be particularly observed that the slide carrying the toggle means is non-detachably engaged with the post and consequently removable only when the latter is withdrawn from the ground socket. The arrangement does not therefore lend itself very well to embodiment with permanently fixed posts, particularly posts of wood; and it is with a view toward overcoming this disadvantage that the present invention is directed. In other words, I aim to provide a net stretching device which is applicable to permanently fixed posts and wherein the slide that carries the net tensioning means is detachable from the post.

Further objects and attendant advantages will be manifest from the detailed description following when considered with the drawings, wherein Fig. I is a perspective view of a tennis net stretching device conveniently embodying my invention; and,

Fig. II is a detail sectional view, taken as indicated by the arrows II-II in Fig. I.

With more specific reference to the illustrations, my improved tennis net stretching device comprises a guide or attaching member in the form of a plate 10 which is secured, by means of screws 11, to the outer face of one of the supporting posts P between which the net is spanned. As shown, the guide plate 10 affords a counter-recessed longitudinal groove 12 for vertical guidance of a laterally projecting slide member 13

which carries a pin 14 in an embossment 15 at its lower end, said pin being adapted for selective registry with apertures 16, arranged as a vertical series medially of said guide plate. A helical compression spring 17 (Fig. II) concealed in the hollow of the embossment 15 tends to yieldingly maintain the pin 14 in the selected aperture 16; and to enable manipulation incidental to positional shifting of the slide member 13, said pin is provided at its outer end with a finger knob 18. An integrally formed laterally projecting arm 19 at the top of the slide member 13 has its outer end flattened as at 20 for fulcrum attachment at 21 of an actuating lever handle 22. Pivotally connected at a point 23 about midway of the length of the lever handle 22 for capacity to swing over the fulcrum 21, is a yoke link 24, said link having an eye 25 projecting from its arch top for attachment of the upper net rope R. A rounded metallic protective cap piece 26 is fastened by screws 27 to the top of the post P, and provides a groove 28 within which the rope R is free to reeve when the tennis net is tightened in the manner hereinafter explained.

In the use of my invention, the lever handle 22 is swung upward about its fulcrum 21, and while in this position, the pin 14 is withdrawn against the influence of the spring 17 and the slide member 13 thereupon moved downward in the guide slot 12 of the plate 10 until the net is fairly taut. The pin 14 is thereupon released to engage the nearest hole 16 in the plate 10 to lock the slide 13, and the lever handle 22 finally depressed to the position illustrated with attendant placement of the rope R under tension, in a manner quite obvious from Fig. I. Incidental to the described action, the yoke link 24 is moved as shown to an angular position inward of the fulcrum axis 21 of the handle 22 so that the latter is thereafter arrested against outward displacement under the tension of the rope R. When the rope R becomes slack from time to time as a consequence of being continuously subjected to longitudinal strain, the above described op-

eration is simply repeated as often as required.

Having thus described my invention, I claim:

- 5 1. In means for stretching a tennis net, the combination of a grooved base with a series of apertures therein, a slide afforded guidance in said base having a projecting arm and associated embossment, retractable 10 spring-influenced locking means in said embossment selectively engageable in any one of the series of base apertures, and means fulcrumed to the outer end of the projecting arm for attachment of the tennis net 15 rope whereby said net may be tensioned.
2. In means for stretching a tennis net, the combination of a counter-recessed grooved base with a series of medially located apertures therein, a slide movable in 20 the grooved base having a projecting arm and associated hollow portion, a retractable spring-influenced locking member mounted in said hollow portion and selectively engageable in any one of the series of base 25 apertures, and net stretching means pivoted to the outer end of the projecting arm aforesaid for attachment of the tennis net upper rope.
3. In means for stretching a tennis net, the combination of a counter-recessed longitudinally-grooved base with a series of medially located apertures therein, a slide afforded vertical guidance in the grooved base, said slide embodying a laterally projecting arm and a paralleling hollow portion, a retractable spring-influenced pin axially movable in the hollow portion for selective engagement in any one of the series of medially-located base apertures, and 40 means fulcrumed to the outer end of the projecting arm for attachment of the tennis net upper rope.
4. In means for stretching a tennis net, the combination of a counter-recessed longitudinally-grooved base with a series of medially located apertures therein, a slide afforded vertical guidance in the grooved base, said slide embodying a laterally projecting arm and a paralleling hollow portion, a retractable spring-influenced pin axially movable in the hollow portion for selective engagement in any one of the series of medially located base apertures, a protective cap for securement to an associated supporting post constituting a guide for the net rope over the top of said post, and means fulcrumed to the outer end of the projecting arm whereby the tennis net 50 may be desirably tensioned.
- 60 60. In testimony whereof, I have hereunto signed my name at Ardmore, Pa., this 6 day of Sept., 1928.

GEORGE L. LANE.
